UNITED STATES PATENT OFFICE.

AUGUSTUS G. PACE, OF SEATTLE, WASHINGTON.

GAS AND OIL ENGINE.

1,404,718.

Specification of Letters Patent. Patented Jan. 24, 1922.

Application filed April 28, 1920. Serial No. 377,217.

To all whom it may concern:

Be it known that I, AUGUSTUS G. PACE, a citizen of the United States, residing in the city of Seattle, in the county of King 5 and State of Washington, have invented certain new and useful Improvements in Gas and Oil Engines, of which the following is a specification.

This invention relates to gas and oil engines, the object of the invention being to provide an improved engine in which the exhaust is utilized in conjunction with fresh combustible, whereby increased powers and material economy are obtained.

15 A further object of the invention is the provision of an improved organization of mechanism in which the heat of the exhaust is used to gasify the heavy oil by being drawn into the piston cylinder then carried into the fresh oil and air.

20 A further object of the invention is the provision of an improved engine which may be started by means of one fluid and after starting run by means of another fluid 25 comprising a mixture of oil and air commingled with a mixture comprising the exhaust.

25 A further object of the invention is an improved engine so organized that during 30 the major part of one stroke of the piston combustible material will be drawn into the cylinder and during the rest of such stroke exhaust will be drawn in to be compressed with such fresh material prior to ignition, 35 thus adding to the charge from the beginning of the compression stroke of the pistons and increasing the weight of the charge and increasing the mean temperature of the working fluid by the presence of hot 40 exhaust gases which causes the mixture to have less fresh air, thereby increasing the temperature of the explosion, also utilizing the unburnt products of combustion which form part of the exhaust.

45 In the drawings accompanying and forming part of this specification, Fig. 1 is a top or plan view of this improved engine, Fig. 2 is a front elevation thereof, parts being broken away to more clearly illustrate 50 the subject matter of the present improvement. Fig. 3 is a vertical section view taken in line A. A. Similar characters of reference designate corresponding parts of all the figures of the drawings.

55 The present invention is in part an improvement upon the subject matter shown

and described in my Patent No. 963,318, dated July 5, 1910. As a preface to a further description of the present improvement, I desire to state that the organization herein shown and described may be more or less varied without departing from the scope of the invention, which comprises in a general way embodying piston, mechanism, cylinders and valve mechanism so organized that 60 for an appreciable part of the stroke of the pistons in one direction fresh combustible material, such as air and oil, will be drawn in the cylinder and then during the remainder of the stroke of such piston in the 65 same direction exhaust products of combustion previously driven from the cylinder will be drawn into the cylinder with the fresh combustible material previously drawn in and then compressed and upon the completion of compressing ignited by any suitable form of igniter.

The present engine is shown as a four-cycle two cylinder engine 1 and 2, each cylinder having a suitable casing 3 which 80 forms a water jacket around the cylinder for cooling purposes, the said cylinders being supported by suitable frame work 4.

Located in each cylinder is a piston 5. The pistons 5 are connected by suitable connecting rods 6 to crank shaft journaled in the frame work.

Each piston is suitably provided with packing rings 8 to form an air-tight connection with the walls of its piston cylinder.

90 Leading to each cylinder is a pipe or passage 9 for the admission of warmed air from around exhaust pipe 10 passing through valve 11 and holes 12, the heated air passing the oil jet 13, causing the oil 95 to spray into passage 14, the oil being supplied to the oil jet 13 by means of supply floats 15 and 16. A cock 17 to use the oil from either supply float 15 or 16 as may be desired. The air and oil mixture then 100 passes through the valve 37 controlled by the governor mechanism 18, which is connected to the crank shaft 7 by belt or chain 19. The oil and air mixture then passes to the exhaust heated inlet pipe 20, the heat 105 being supplied by admitting exhaust from the exhaust pipe 10 to pipe 21, which carried the hot exhaust to casing 22 which surrounds the inlet pipe 20, thereby heating the inlet pipe 20. A small hole 23 is provided to vent the exhaust to pipe 20 so as to 110 maintain an even temperature in casing 22.

The exhaust that passes through the small hole 23 mixes with the oil and air mixture and then passes to the cylinder through the inlet valve 24 which is held closed by 5 spring 33 and opened by suitable cams carried by cam shaft 25 suitably supported in the frame work.

When the piston 5 is about half-way down on the suction stroke, the exhaust valve 27, 10 which is held closed by spring 34, is opened by a suitable cam carried by cam shaft 26 and remains open during the remainder of the suction stroke supplying hot exhaust gases to the air and oil mixture within the 15 cylinder furnishing the heat necessary to gasify the heavier oil or fluid, also to reduce the excess of air in the explosive mixture thereby increasing its explosive temperature.

The exhaust passage is shown communicating with the atmosphere by means of pipe or passage 10. The exhaust valve 27, which is held closed by spring 34 is opened by a suitable cam carried by cam shaft 26 suitably supported in the frame work.

25 The igniters 28 are connected by suitable commutators 35, being arranged that the spark may be advanced or retarded at the will of the operator.

Inasmuch as my present improvements relate chiefly to features of construction not requiring any particular kind of crankshaft or connections therefrom to the pistons of the cylinder, I have herein, and particularly in some of the claims, employed the term 30 "Piston Mechanism" for indicating that part of the engine which comprises the pistons in the cylinder respectively and some suitable means for connecting such pistons with transmitting devices suitable for delivering the power from the engine for use.

Having thus described my invention, I claim:

1. In an engine of the character described, the combination with a cylinder provided with passages for admitting fresh combustible material thereto and discharging the exhaust gases therefrom, of means for simultaneously reintroducing said exhaust into the cylinder through each of said passages.
2. In an engine of the character described, the combination with a cylinder provided with passages for admitting fresh combustible material thereto, and discharging the exhaust gases therefrom, of valve mechanism

for controlling the flow through said passages, piston mechanism for said cylinder, means for reintroducing a small portion of the exhaust gases into the cylinder through said intake passage during the major portion of one stroke of said piston, and means for reintroducing a large portion of the exhaust gases into the cylinder through said exhaust passage during a minor portion of said stroke.

3. In an engine of the character described, the combination with a cylinder provided with passages for admitting fresh combustible material thereto and exhaust gases therefrom, of means for reintroducing different amounts of the exhaust gases into the cylinder through said passages.

4. In an engine of the character described, the combination with a cylinder provided with passages for admitting fresh combustible material thereto and exhaust gases therefrom, piston mechanism for said cylinder, means for introducing a mixture of said material and a small amount of said gases into the cylinder through said admission passage during substantially the full suction stroke of said piston, and means for reintroducing a large amount of the exhaust gases into the cylinder through said exhaust passage during the completion of said stroke.

5. In an engine of the character described, the combination with a cylinder provided with passages for the admission of a combustible fluid thereto and the discharge of the exhaust gases therefrom, piston mechanism for said cylinder, a chamber surrounding said fluid intake passage and communicating with said exhaust gas passage, a passage connecting said intake passage with said chamber whereby a small amount of the exhaust gases may be mixed with said fluid and introduced into the cylinder during the suction stroke of said piston, and means for reintroducing the exhaust gases into the cylinder from said exhaust passage during the final period of said stroke.

Signed at #4714 6th Avenue N. E., Seattle, Washington, this 23 day of April, 1920.

AUGUSTUS G. PACE.
